(57) **CLAIM**

The ornamental design for a stool, as shown and described.

DESCRIPTION

FIG. 1 is a perspective view of a first embodiment of a stool.

FIG. 2 is a front view thereof.

FIG. 3 is a back view thereof.

FIG. 4 is a first side view thereof.

FIG. 5 is a second side view thereof.

FIG. 6 is a top view thereof.

FIG. 7 is a bottom view thereof.

FIG. 8 is a perspective view of a second embodiment of a stool.

FIG. 9 is a front view thereof.

FIG. 10 is a back view thereof.

FIG. 11 is a first side view thereof.

FIG. 12 is a second side view thereof.

FIG. 13 is a top view thereof.

FIG. 14 is a bottom view thereof.

FIG. 15 is a perspective view of a third embodiment of a stool.

FIG. 16 is a front view thereof.

FIG. 17 is a back view thereof.

FIG. 18 is a first side view thereof.

FIG. 19 is a second side view thereof.

FIG. 20 is a top view thereof.

FIG. 21 is a bottom view thereof.

FIG. 22 is a perspective view of a fourth embodiment of a stool.

FIG. 23 is a front view thereof.

FIG. 24 is a back view thereof.

FIG. 25 is a first side view thereof.

FIG. 26 is a second side view thereof.

FIG. 27 is a top view thereof; and,

FIG. 28 is a bottom view thereof.

The broken lines in the drawings illustrate portions of the stool and form no part of the claimed design.

1 Claim, 28 Drawing Sheets

Related U.S. Application Data

division of application No. 29/708,937, filed on Oct. 10, 2019, now Pat. No. Des. 935,214.
